UNITED STATES PATENT OFFICE.

JOHN BURNS, OF KENOSHA, WISCONSIN, ASSIGNOR TO THE SIMMONS MANUFACTURING COMPANY, OF KENOSHA, WISCONSIN, A CORPORATION OF WISCONSIN.

BED FABRIC.

1,128,581.

Specification of Letters Patent. Patented Feb. 16, 1915.

Application filed June 22, 1914. Serial No. 846,440.

To all whom it may concern:

Be it known that I, JOHN BURNS, a citizen of the United States, residing at the city of Kenosha, in the county of Kenosha and State of Wisconsin, have invented certain new and useful Improvements in Bed Fabrics, of which the following is a specification.

My invention relates to improvements in bed fabrics and refers more particularly to a type of bed fabric which is composed of a series of longitudinal chains tied together by cross-links and so organized that it may be folded both transversely and longitudinally.

Among the salient objects of the invention are, to provide a bed fabric in which the longitudinal and cross-links of the fabric are arranged in interhooked engagement in such a manner that there is no possibility of the links creeping, slipping or becoming displaced while the fabric is in its normal flat condition or when it is folded either transversely or longitudinally; to provide a construction in which there is no tendency for the links to open up or spread apart, due to any longitudinal or transverse stress to which the fabric is subjected; to provide an improved construction of the links which will admit of their manufacture by comparatively simple automatic machinery in an efficient, economical and rapid manner; to provide an improved form of link which may be manufactured without waste of wire caused by complicated, unnecessary bends or twists; and, in general, to provide an improved wire link bed fabric of the type referred to.

My invention consists in the matters hereinafter described and more particularly pointed out in connection with the accompanying drawings, in which—

Figure 1 is a plan view of a portion of a wire link bed fabric embodying my improved construction; Fig. 2 is a longitudinal section taken on the line 2—2 of Fig. 1; and Fig. 3 is a transverse section taken on the line 3—3 of Fig. 1.

In the drawings I have illustrated a portion of a wire link bed fabric which comprises longitudinal chains composed of interhooked longitudinal links 4 which are tied together transversely by means of cross-links 5. All of the longitudinal links 4 are

alike, and each is constructed of a length of wire which is centrally bent to form a completely closed eye 6. This eye forms a central convolution at one end of the link, and is in the form of an isosceles triangle the two equal angles of which form bights for the reception of the hooks 7 at the ends of the cross-links 5. The crossed ends 8 and 9 of the closed loop 6 project from the latter a short distance and are then both reversely bent at an acute angle to form the upper bights 10. The ends of the wire are then brought down adjacent to the sides of the convolution 6 and the extremities of the wire are furnished with hook ends 11 which engage the bights 10 in the adjacent end of the next link in the chain. The inner portion of the convolution 6 is in the same plane as the two sides 12 of the link so as to make it convenient to apply the cross-links 5, and the two crossed portions 8 and 9 are slightly bent away from each other at the intersection so as to cause the bights 10 also to occupy the same plane as the wires 12 and the inner portion of the loop 6. The hooks 7 in the ends of the cross-links 5 are large enough to permit the fabric to hinge freely in a transverse direction and the hooks 11 in the longitudinal links are in a similar manner made large enough to facilitate longitudinal flexing of the fabric. It will be noticed that the elbows 10 into which the hooks 11 of the longitudinal links are engaged, are completely closed so that the hooked ends of the longitudinal links cannot creep, slip or become displaced; and it is also obvious that the hook ends of the cross-links 5 cannot escape or creep out of the completely closed convolution forming the triangular eye space 6. In fabrics of this type the longitudinal chains receive most of the stress, and it is consequently of considerable importance to shape the links composing them in such a manner as to prevent them from bending or opening up, due to severe tension. This requirement is well taken care of in my improved fabric since the sides of the link which transmit the pull are entirely free from kinks, bends or twists.

My improved form of link is particularly easy to construct by means of comparatively simple automatic machinery, since the central convolution or coil is formed by simply

bending the wire at two points and then reversely bending the two projecting ends; and there is no waste of wire caused by the introduction of unnecessary, complicated 5 twists or bends.

It will be manifest to those skilled in the art that my construction is capable of being varied somewhat without departing from the spirit of the invention, and consequently 10 I do not limit myself to the exact details of construction described or shown except as specified in the appended claims.

I claim—

1. A bed fabric chain composed of twin-
15 wire links, each having at one end, lying in the plane of and between the side wires, a closed loop-eye, the continuations of the wire forming the loop-eye crossing each other and being bent back into parallelism
20 closely adjacent the eye, to form with the latter a pair of closed bights, and hook-loops on the terminal ends of said twin

wires engaging the bights of the next similar link in order.

2. A wire bed fabric, composed of longitudinal links and cross-links, each longitudinal link being formed from a length of wire centrally bent upon itself to form a central completely closed eye, the contiguous parts of the wire crossing each other at an angle and being reversely bent at an acute angle to lie alongside and on either side of said closed eye to form separate adjacent bights at the end of the link, the extremities of the wire forming the side bars of the link and being bent into hooked engagement 25 with the bights in the adjacent link of the chain, and cross-links engaging said central eyes for tying the chains together. 30 35

JOHN BURNS.
